UNITED STATES PATENT OFFICE.

CHARLES S. WHEELWRIGHT, OF BRISTOL, RHODE ISLAND, ASSIGNOR TO
AMERICAN EXTRACTOR COMPANY, A CORPORATION OF MAINE.

RENDERING APPARATUS.

SPECIFICATION forming part of Letters Patent No. 783,560, dated February 28, 1905.

Application filed June 17, 1904. Serial No. 212,974.

To all whom it may concern:

Be it known that I, CHARLES S. WHEELWRIGHT, of Bristol, in the State of Rhode Island, have invented a new and useful Improvement 5 in Rendering Apparatus, of which the following is a specification.

The process conducted by the new apparatus is mainly the hot-water process conducted by apparatus described in my applications 10 Serial No. 179,382, filed October 31, 1903, and Serial No. 209,553, filed May 24, 1904; but provision is made, as will hereinafter fully appear, for using again and again the same water both for cooking the garbage or offal and re- 15 moving the melted grease and for washing the tankage.

The invention consists in the use, with several digesters and water and oil receivers adapted to separate melted grease from garbage or offal by the hot-water process and water-extractors adapted to separate water used in the digesters from the tankage, of a hot-water tank and a force-pump both common to said digesters and extractors, the said hot-water 25 tank being a vessel adapted to resist steam-pressure, having its top above the top of the digesters and having a conical-shaped bottom just above the level of the tankage-exit at the bottom of the digesters and also having a pipe 30 communication with said digesters near its top and the top of said digesters and a pipe communication from its cone-shaped bottom with said tankage-exit below the valve therein between said digester and its said water-extractor 35 and the force-pump being provided with suction and discharge pipes and adapted, by means of said suction and discharge pipes, to take water flowing from said digesters and said common hot-water tank into said water- 40 extractor and return it to any of said digesters or to said hot-water tank.

The invention consists also in certain details of construction.

In the drawings hereto annexed and forming a part of this specification, I represent the hot-water tank and force-pump as used with but a duplicate set of digesters, receivers, and extractors; but it will be evident that within 45 my invention the same tank and pump might

be used with a greater number of digesters, 50 receivers, and extractors, and it will be observed that where the apparatus is duplicated the same letter is used to designate a similar part in either apparatus, except as will be obvious.

Figure 1 is a side elevation of an apparatus embodying the invention. Fig. 2 is a front elevation of the same. Fig. 3 is an enlarged longitudinal section of the extractor. Fig. 4 is a cross-section of the same further enlarged. 60 Figs. 5 and 6 are details.

A is one of the digesters. A' is the other digester.

B B' are the two water and grease receivers.

C C are two water-extractors, one being required for each digester.

D is the hot-water tank common to both digesters, and N is the force-pump, also common to both digesters.

B² is a stand-pipe opening from the top of 70 the digester and extending within the receiver to near the top thereof and having in its own top a charcoal filter B³. The stand-pipe B² is the operative leg of a trap, since water and oil passing upward through the stand-pipe and 75 filter fall, over into the receiver, in which they are thus trapped. At the bottom of the stand-pipe B², or in a prolongation thereof, there is a valve operated by a hand-wheel, through which communication between the digester and the 80 stand-pipe and receiver may be opened or closed. This valve, or rather the hand-wheel by which it is operated, is marked V.

The designating-letter of valves in this application is applied indifferently to the valve 85 or to the shell within which it is operated or to the wheel by which it is operated.

B⁴ is a cover to the receiver.

B⁵ B⁶ are posts upon which the receiver is supported on the top of the digester.

P is a pipe through which melted grease may be drawn off at different heights through valves v^a v^b v^c from the receiver.

P' is a water-pipe provided with valve V', through which water may be drawn off or 95 blown off from beneath melted grease in the receiver into a pipe P², whose office will be hereinafter described. This pipe P² has a valve

V². The corresponding pipe and valve belonging to the receiver of digester A' are marked P³ and V³. The receiver B is furnished with a thermometer b and a pressure-gage b' and also with a water and grease gage b². P⁴ is a pipe by which water may be blown off from the top of the digester into the said pipe P², as will presently more fully appear. It has a valve V⁴. The digester A' has a similar pipe P⁵ and valve V⁵.

The digester A is formed in sections, as shown. The upper sections are dome-shaped, as shown.

A² is a suitable entrance-hole near the top 15 of the digester for the admission of the garbage or offal.

A³ is a strainer provided with large hanging teats or blades such as are described in my Patent No. 709,836, dated September 23, 20 1902. It lies across the digester just above the entrance-hole A².

A⁴ is a properly-closed manhole through which the strainer A may be placed in position or taken out to be cleaned.

25 The lower section of the digester A is cone-shaped, as shown. It is surrounded by a steam feed-pipe P⁶, which is fed by main steam-pipe P⁷, valved at V⁷, and by branches furnishes the steam to the digester for cooking 30 through valves v⁴ v⁵ v⁶, &c., bosses a a a being cast on the cylinder and properly bored for the reception of the said branch entrance-pipes. The two circular pipes P⁶ P⁶, surrounding, respectively, the lower cones of the two 35 digesters A A', are connected by a pipe P⁸, having at either end a valve V⁸ V⁹. With pipe P⁸ connects the above-mentioned pipe P², extending between the two digesters A A' from the top of the system. It has a check- 40 valve V¹⁰ near its connection with pipe P⁸. By manipulating the valves V⁴ V⁵ in the above-mentioned pipes P⁴ and P⁵, together with valve V² in pipe P², hot water or steam in either 45 digester may be directed from the top of one digester to the bottom of the other. The top of the pipe P² communicates with the thermometer b and pressure-gage b' by an extension P⁹, valved at valve V⁹, as shown. The digester has a tankage-exit through a large 50 pipe P¹⁰, furnished with a large valve V¹⁰.

E is the shell or cylinder of the kind of water-extractor C which I use and prefer to use in my combination, although any steam-tight water-extractor in which water separating 55 from the tankage may be made to feed a force-pump will come within my claims to invention. The particular water-extractor here described forms the subject-matter of my said application Serial No. 209,553, filed 60 May 24, 1904. Water is separated from the tankage in said water-extractor and pumped either to the digester in which it was first used or another digester or to the common hot-water tank D. It will be observed that 65 the object of this invention is the preserva-

tion of this water that it may be used again in its heated condition in the digester from which it came or in some other digester of the system or in an extractor without passing through either digester. The cylinder E has 70 an entrance-hole at E', with which the large pipe P¹⁰, leading from the digester A and forming the tankage-exit, connects. It is provided with lugs e e, by which it is supported on standards F. It is provided with 75 a screw G, closely fitting its inner periphery, and is suitably keyed to a shaft G', having bearings in the movable tailpiece E² of the cylinder and in a standard F' at its extreme farther end. The cylinder E is provided with an extension E³ beyond the farther end of the screw G and with a second extension E⁴ beyond the first, the said second extension being provided with an exit E⁵ (for the tankage from which the water has been 80 largely removed) and with a head E⁶. The extensions E³ and E⁴ may be considered a continuation of the cylinder E, and tankage received by the screw G and carried along 85 through the cylinder by said screw and accompanying devices, as will be explained, would pack in said compartments E³ and E⁴ against said head E⁶; but said head is provided with a valve K, which intervenes between said head and the end of the screw and 90 by means of a spline and feather revolves with the screw. The valve K has a further movement to and from the end of the screw G, which will next be described. In the said head of the cylinder E⁶ is fitted a packing-box 95 I, provided with a gland I', the office of which is to furnish a suitable packing or bearing of a hollow shaft J, moved on and along the shaft G' by a hand-wheel J', a nut J², rigidly connected with said hand-wheel, and a screw-thread on said shaft G'. The said movable hollow shaft J is rigidly connected with the valve K, which is provided with teeth K' K', as shown. The valve K, whatever may be its 100 position longitudinally in extension E⁴, constantly revolves with the shaft G', and thereby with the help of the teeth K' K' breaks up the material forced forward by the screw G and directs it toward the outlet E⁵. The valve K has a seat at L in the rim of the extension 105 of the cylinder E³, and the peculiar shape of the face of the valve K directs material sent forward by the screw G and packed or packing in extensions E³ and E⁴ downward out of the outlet at E⁵ at any position of the valve 110 as removed any distance from its seat by manipulating hand-wheel J'. The valve K has a seat at L in the rim of the extension 115 of the cylinder E³, and the peculiar shape of the face of the valve K directs material sent forward by the screw G and packed or packing in extensions E³ and E⁴ downward out of the outlet at E⁵ at any position of the valve 120 as removed any distance from its seat by manipulating hand-wheel J'. The shaft G' carries a large bevel-gear G², into which takes a small bevel-gear (not shown) carried upon the counter-shaft of the 125 driving apparatus.

M M are two suction-boxes similar to those used in Fourdrinier paper-machines. N' N' are suction pipes or outlets for said boxes, and O O are perforated plates set into and 130

forming a part of the cylinder E, through which water flows into said suction-boxes or is drawn into said boxes by means of the said force-pump N acting through said suction-pipes N' N'. To the pump N is connected a discharge-pipe P¹¹, provided with valves and branches, as shown, and by manipulating the said valves (hereinafter designated and described) the same water which has been sucked from the cylinder E by the suction-boxes M M may be returned in a heated condition to the top of the digester A, through which it had previously passed, or to the top of the hot-water tank D.

15 The suction-pipes N' N' are provided with valves V^u and V^u, as shown, and the discharge-pipe P¹¹ has near its top a valve V^u.

As before stated, D is the hot-water tank, being a long steam-tight iron tank conveniently situated with reference to the digesters and extractors of the system. Its top extends a considerable distance above the tops of the digesters, and its bottom, which is cone-shaped, is somewhat above the tankage-exit pipes P¹⁰ of the digesters, with which it communicates by pipes P¹² and P¹³, branching from the bottom of its cone. The pipes P¹² and P¹³ have each a check-valve V^k and V^l and ordinary cut-off valves V¹² and V¹³. The hot-water tank D is provided with a strainer D' near the top above all inlets to said tank. It has also on its top a stand-pipe D², which within the limit of the action of the force-pump N is provided with a pipe P¹⁴, valved at V¹⁴, leading to a closed tank T, which may be connected with an ammonia-saving machine. (Not shown.) The stand-pipe D has a water-gage b⁴ to indicate the condition of the water.

20 The discharge-pipe P¹¹ of pump N extends to near the top of the digesters and hot-water tank, connecting directly with the latter, as shown, and through branches P¹⁵ and P¹⁶ with the two digesters. In the arrangement of two digesters shown these pipes are provided with valves V¹⁵ V¹⁶, by the manipulation of which and valve V¹¹ water may be pumped into the hot-water tank or into either of the digesters.

25 The main office of the hot-water tank will now be described. This tank is supposed to have received a large supply of hot water, which has been mostly blown into it from the surplus water used in the digester for cooking the garbage and floating off the grease, the valves V¹² and V¹³ in the pipes leading from the bottom of the tank having remained closed. The cooking having been accomplished, the operator closes the valve V between the digester A and the receiver B and shuts off live steam from the digester by closing valve V⁷ in main steam-pipe P⁷. He now by opening valve V¹ in pipe P¹, valve V² in pipe P², and valve V^u in pipe P⁸ (closing valve V⁵ in pipe P⁵ and valve V⁸ in pipe P⁸) permits steam and water 30 to be blown off from the digester A, in which

the cooking has been completed, into digester A', which is charged with a fresh supply of garbage ready for cooking, until the pressure between the two digesters is equalized, when valve V⁴ in pipe P⁴ is closed. Valve V¹⁵ in pipe P¹⁵ and valve V¹¹ in pipe P¹¹ are now opened, opening a passage from digester A to the hot-water tank D, and all further pressure remaining in the digester in which the cooking has been completed is blown off into the hot-water tank. Digester A having been relieved of its pressure, the operator opens valve V in pipe P at the bottom of the receiver and blows down the pressure in the receiver without draining off any grease to a point where he 35 may open the large connecting-valve V between the digester and receiver, so as to relieve all pressure in the digester without disturbing the grease. He is now prepared to draw the solid matter from the bottom of the digester. He first goes to the water-extractor and closes the valve K upon its seat. He then opens valve V¹² in the pipe P¹², leading from the hot-water tank to the tankage-exit P¹⁰ of the extractor-cylinder to the suction-pump N. Valve V¹⁵ in the branch discharge-pipe P¹⁵, leading into the side of the digester, remaining open, (valve V¹¹ being closed,) valves V^u V^u are opened, and the pump N is started and hot water is delivered into the digester until it is indicated by the water-glass b³, attached to the receiver. After a few minutes power is started on the water-extractor and then the plug-valve K is drawn back in the discharge end of the extractor, allowing solid tankage to pass out, the suction-pump drawing out the water and discharging it back into the digester. A portion of the water passes off with the solid matter out of the extractor, and owing to the displacement of the solid matter the return-water will not keep up the supply or head, (so as to permit the flow of accumulating grease in the digester to be delivered into the receiver.) Accordingly the operator from time to time allows hot water from the hot-water tank to flow into the extractor by opening valve V¹² in pipe leading from the said tank to the discharge-pipe P¹⁰ of the digester in such quantities as to keep up the flow from the digester to the receiver, as indicated by the water-glass. When the digester has been freed from solid matter, the operator shuts the valve V¹⁵ in the branch discharge-pipe of the pump leading into the digester and opens the valve V¹¹ in the pipe leading into the hot-water tank, and draws from the extractor C into the hot-water tank, leaving water enough for a cushion in the digester for the next charge.

40 It will have been observed that the apparatus thus far described is steam-tight and that during the passage through it of the garbage or offal and of water employed for the purposes stated no opportunity is afforded for

the escape of foul odors. There are but two outlets shown, one a valved chimney on the top of the stand-pipe D² (the valve in the chimney is not shown) and the other the outlet to the extractor. With the latter may be connected a drying apparatus and a similar chimney, both said chimneys connecting with any suitable gas and vapor condenser.

- Although the suction-boxes M M are not the subject of claim herein, being claimed in my said application Serial No. 209,553, it is thought well to describe the method of their attachment to the cylinder E. This is shown at Figs. 3 and 4, where M, as before, is one of the suction-boxes, and O is a perforated plate set into the cylinder E. M' is one of several bars to support or hold up the perforated plate O, the said bars being cast with the box M. The box M is hinged to the cylinder E (see Fig. 6) by means of two lugs e⁴ e⁴, cast on the cylinder, a fork m m, cast upon the box M so as to fit inside of said lugs e⁴ e⁴, and a bolt m', passing through the said fork and lugs and also through an eccentric n², which fits between the lugs e⁴ e⁴ and is swung by a lever n³. When the box is set free at the other end, as will now be described, and the eccentric n² is loosened by swinging back the lever n³, the box swings back on the bolt m', carrying with it the supporting-bars M'. The office of the eccentric n² is to tighten the box M in its working position. The locking apparatus at the other end of the suction-box (see Fig. 5) consists of two lugs e⁵ e⁵, cast upon the cylinder E, a swivel-pin n, pivoted by a bolt n' to the said lugs e⁵ e⁵, and embraced by forked arms n⁵ n⁵, which are cast upon the box M and are held in the position embracing said swivel-pin by a nut n⁴, working on a screw-thread on the end of said swivel-pin and operated by a handle n⁶.

The office of the screw G, as has perhaps already appeared, is to carry forward in the cylinder, or through the cylinder and extensions thereof, the more solid parts of the contents of the cylinder; but this the screw sometimes fails to do, owing to the lubricant nature of such material or substance. The greasy mass is apt to turn with the screw without being moved forward. This difficulty is in part remedied by the frictional resistance imparted to the mass by the above-mentioned suction-boxes M M, a pull or suction being exerted upon the mass in a direction contrary to force exerted by the screw.

Another device for imparting frictional resistance to the slippery material held in the thread of the screw consists of certain movable pieces of metal which I term "vibrating fins" R R, whose movements into and out of the mass are controlled by the screw acting upon their edges automatically. These fins are very numerous and are placed in pairs about the screw, (see Figs. 1 and 3,) so that a separate fin works in each interval between

two screw-threads. They are made of soft metal and have their peripheries cam-shaped, as shown, so as to follow with an up-and-down or in-and-out vibrating motion the convolutions of the screw, the points and heels of the fins dipping into the lubricant slippery mass forced forward by the screw between the threads and rising therefrom successively one fin after another, so that the material between the screw-threads is struck by the fins in various positions. They are so secured to the cylinder that they and the mechanisms by which they are attached may be readily removed. One form of these fins, with accompanying parts, is shown in detail at Fig. 4, where R is the fin pivoted upon axis R', as shown. E is the cylinder. R² R² are long guides let into the cylinder, as shown, for two fins, and held in place by screw-bolts R³ R³, secured by nuts R⁴ R⁴. A long cap R⁵ covers the said two guides R² R², and the space in which the fin works, as shown, being held in place by a lever R⁶, forked at q, where it is pivoted on a pivot-pin q', held in place by nuts q² q². The other end of lever R⁶ is forked at q³ to embrace a swivel-pin R⁷, pivoted on pivot q⁴ and held in place in the fork q³ of lever R⁶ by a nut R⁸, working on a screw-thread on the end of swivel-pin R⁷, and provided with a hand-lever R⁹. The pivot-pin q' has bearings in shoulders R¹⁰, and the pivot q⁴ has bearings in shoulders R¹¹, the said shoulders R¹⁰ and R¹¹ being ears or lugs cast on the guides R² R². The said fins are not the subject of claim herein, being claimed in my said application Serial No. 209,553.

I claim—

1. The combination with several cooking-digesters and water and grease receivers adapted to separate melted grease from garbage or offal by the hot-water process, and water-extractors adapted to separate water used in the digesters from the tankage, of a hot-water tank and a force-pump, each common to said digesters and extractors, the said hot-water tank being a vessel placed alongside of said digesters and adapted to resist steam-pressure, having its top above the top of the digesters and having a conical-shaped bottom above the level of the valved tankage-exit at the bottom of the digesters, and also having valved-pipe communication between the tops of said digesters and the top of said hot-water tank and a pipe communication from said conical-shaped bottom with said tankage-exits below the valve therein between said digesters and water-extractors, and the said force-pump being provided with suction and discharge pipes and adapted by means of said suction and discharge pipes to take water flowing from said digesters and said common hot-water tank into said water-extractors and return it to any of said digesters or to said hot-water tank, substantially as described.

2. The combination of several cooking-di-

gesters and water and grease receivers adapted to separate melted grease from garbage or offal by the hot-water process, and water-extractors adapted to separate water used in the 5 digesters from the tankage, of a hot-water tank and a force-pump, the said hot-water tank being a vessel placed alongside of said digesters and adapted to resist steam-pressure, having a conical-shaped bottom above the level 10 of the valved tankage-exits at the bottom of the digesters, and also having a pipe communication from said conical-shaped bottom with said tankage-exits below the valve therein between each digester and its said water-extractor, and the said force-pump being provided with suction and discharge pipes and adapted by means of said suction and discharge pipes to take water flowing from said digesters and said common hot-water tank into said 15 20 25 water-extractor and return it to any of said digesters or to said hot-water tank, substantially as described.

3. The combination with a digester adapted to cook garbage or offal by the hot-water process, a trapped receiver adapted to receive the

melted grease floated by the hot water used in the said process, and a water-extractor adapted to separate water from the tankage after the grease is floated off from said garbage or offal, of a hot-water tank and force-pump, the said force-pump being provided with suction and discharge pipes and adapted by said suction and discharge pipes to take water flowing from said digester and said hot-water tank and return it to the top of said digester or the top of the hot-water tank, and the said hot-water tank being provided with a valved-pipe connection between the bottom thereof and the valved tankage-exit of the digester leading to said water-extractor, and also with a valved-pipe connection between the upper portion thereof and the upper portion of the digester, there being a filter in said hot-water tank above the entrance of said last-named pipe connection, substantially as described. 30 35 40 45
